UNITED STATES PATENT OFFICE

ABRAHAM LEICHTER, OF NEW YORK, N. Y.

ELECTRIC SIGN

Application filed June 2, 1931. Serial No. 541,648.

This invention relates to an electric sign and has for an object to provide an improved construction wherein means are presented for providing a neon sign member and a hooded sign structure.

Another object of the invention is to provide an improved electric sign wherein the sign formation is presented having hooded lamps for illuminating the same and a neon sign arranged adjacent thereto and carried thereby but spaced from any background.

A further object, more specifically, is to provide an electric sign including a neon sign member wherein the transformer is arranged in the housing of the sign and wherein the neon tube structure is associated with changeable sign members which do not present a background to the neon tube sign member.

20 In the accompanying drawing,—

Figure 1 is a perspective view of an electric sign disclosing an embodiment of the invention.

Figure 2 is an enlarged sectional view 25 through Figure 1 on line 2—2.

Figure 3 is a longitudinal vertical sectional view through the sign shown in Figure 1, the section being taken on the line 3—3 of Figure 2.

30 Figure 4 is a sectional view through Figure 3 on line 4—4.

Figure 5 is a sectional view through Figure 2 on line 5—5.

35 Figure 6 is a fragmentary top plan view of part of the sign box shown in Figure 1, but illustrating a modified form of neon tube receiving structure.

Figure 7 is a wiring diagram showing the circuits of the respective electrical members.

40 Referring to the accompanying drawing by numerals, 1 indicates a housing provided with a forward extension 2 which is open at the bottom as illustrated in Figure 1 whereby a hood is provided for the reception of the respective lamps 3 and 4. These lamps are of any desired kind of electric lamps whereby light may be projected downwardly on the sign boards 5 and 6 which sign boards carry removable sliding sign members 7 and 8. Associated with these sign members is

the neon tube sign 9 which is shown as depending from the bottom of the housing or casing 1, though it could be positioned to extend upwardly therefrom or one end if desired. By positioning the sign 9 as set forth, the casing 1 does not act as a background therefor and consequently the sign is merely suspended in the air without a background, thus permitting the best result. In neon tube signs, it has been found that a background fitted closely to the sign produces a hazy effect which is more or less undesirable. By suspending the sign away from any background, the letters or parts thereof show up clearly and distinctly. By the construction set forth, the neon tube sign clearly stands out and also the members 7 and 8 are clearly illuminated, thus giving the effect of an ordinary illuminated sign and the effect of a neon tube suspended away from the background. The sign 9 is of the usual construction including enlarged ends 10 and 11 as shown in Figure 3. Advantage has been taken of the fact that these enlarged ends are essential to the sign and through their use, the sign has been properly supported.

45 As illustrated in Figure 4, the bottom 12 of the casing 1 is provided with notches 13 and 14 extending from one edge to about the center. These notches are the width of the neon tubes of the sign 9 so that the sign may be slid in laterally with enlargements 10 and 11 above the bottom and the remaining part below the bottom. This will cause the bottom of the enlarged portion to rest on the upper surface of the bottom 12. To prevent undue swaying or loose motion 50 of the sign, filling blocks 15 and 16 are provided, said blocks acting as clamping means for rather tightly clamping the sign in place as shown in Figure 4. Each of these blocks is connected to and supported by a flexible member 17 which is swingably secured by rivets or other means at 18 to bottom 12.

55 When it is desired to remove the neon tube sign, the members 17 are flexed upwardly and then rotated until the clamping members or blocks 15 and 16 are out of the way. As the blocks 15 and 16 are secured to the respective members 17, they will be lifted out 60

of the slots 13 and 14 and swung to one side when the flexible members 17 have been moved to one side. The neon tube sign may then be removed and re-applied as desired.

5 After each of the parts has been assembled as just described, the removable back plate 19 is inserted, said back plate being slidably fitted into certain flanges 20 and 21 projecting from the ends of the casing 1. When the plate 19 is inserted, the ends thereof are forced between the respective flanges 20 and 21 and their coacting brackets 20' and 21' whereby the plate is held tightly in position through the action of friction which is ample 15 to hold the plate in position as it is made from very thin material, preferably sheet metal. After the back 19 has been placed in position, the blocks 15 and 16 are locked against shifting movement.

20 Under some circumstances, a slightly different structure is used, namely, the modified structure shown in Figure 6. In this form of the invention, the bottom 12' is provided with an aperture 22 which is of less 25 size than the enlargements 10 and 11 so that as the small part of the sign is forced past the narrow entrance 23, the enlargement may overlap part of the bottom 12' and rest thereon. The bottom part of the enlargements 30 10 and 11 taper somewhat so that they will project into the opening 22 and consequently cannot slide out of the opening.

As is well known, neon tube signs take rather high voltage, as for instance 12,000 volts 35 for a certain length of tube. This high voltage is objectionable where it is to be carried a long distance and consequently the casing 1 is made sufficiently large so that a transformer 24 is mounted in the casing and 40 clamped thereto by suitable bolts 25. This transformer is only large enough to take care of the particular sign 9 and receives the current from any suitable source through the supply cable 26. This supply cable supplies 45 current also at 110 volts or other comparatively low voltage to lamps 3 and 4. Switches 27 and 28 may be interposed in the circuit of lamps 3 and 4 so that they may be turned on and off if desired without affecting the tube 50 sign 9. The high potential current leaves the transformer 24 through the respective wires 29 and 30 and are connected directly to the terminals of the sign as shown in Figure 3. In this way, if the switches 27 and 28 55 are closed, it will only be necessary to turn on current to the sign as a whole and the sign boards 5 and 6 will be illuminated and the sign 9 will receive its proper current. As illustrated in Figure 7, the current entering in through the wires 31 and 32 is distributed respectively to the lamps and the transformer. The wires 31 and 32 are usually arranged into a cable indicated by the cable 26 in Figure 3. In this way, a comparatively low voltage or ordinary house volt-

age is led into the sign and the transformer steps up the current to the desired voltage for the neon sign, while the other electrically actuated devices use the current at line voltage.

70 I claim:

1. An electric sign including a casing formed substantially L-shaped in cross section, one leg of the L being open, electric lamps arranged in said last mentioned leg, 75 a transformer arranged in the other leg of said casing, a sign board carried exteriorly of said last mentioned leg and positioned to be illuminated by said lamps, and a neon tube sign carried by said casing with the main part spaced therebelow, said tube sign being electrically connected with said transformer to receive current therefrom, and means for directing house current into the casing, said means being connected with the transformer and with said lamps.

2. In an electric sign, a casing, conductors for directing current into the casing, a transformer arranged in the casing connected with said conductors, a neon tube sign carried by the casing and connected to the outlet terminals of said transformer, said neon tube sign having enlargements at each end, said casing having a slot near each end for accommodating the end portions of said sign, said enlargements resting on the top of the bottom of the casing adjacent the slot, a clamping block arranged in each slot and means forming part of the casing for locking said blocks in place.
